UNITED STATES PATENT OFFICE.

SAMUEL B. SULLIVAN, OF PITTSBURGH, PENNSYLVANIA.

AUTO LUNCH KIT.

1,326,114.

Specification of Letters Patent. Patented Dec. 23, 1919.

Application filed March 18, 1919. Serial No. 283,366.

To all whom it may concern:

Be it known that I, SAMUEL B. SULLIVAN, a citizen of the United States, residing at N. S. Pittsburgh, in the county of Allegheny and State of Pennsylvania, have invented certain new and useful Improvements in Auto Lunch Kits, of which the following is a specification.

The invention meets the needs of tourists by providing means for satisfying the demands of nature with reference to satiating hunger and quenching thirst.

The invention provides a kit especially adapted to be carried on the running board of an automobile and which will preserve food and drink in a wholesome condition and prevent it spoiling on the hottest day as provision is had for carrying an ample supply of ice and for the circulation of cool air, both of which are essential to keep the food from deteriorating on a warm day.

The invention consists of a case, a box within the case and spaced therefrom and a plurality of receptacles or trays within the box and detachable therefrom to provide for ready access to the food and to enable the parts to be thoroughly cleansed and reached for any desired purpose.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

Referring to the drawings hereto attached.

Figure 1 is a front view of a lunch kit embodying the invention, the top and front of the case being in open position and a portion of the front of the box being broken away.

Fig. 2 is a transverse section on the line 2—2 of Fig. 1 looking to the right, as designated by the arrow.

Fig. 3 is a transverse section on the line 3—3 of Fig. 1 looking to the right, portions of the top and front of the case being broken away.

Fig. 4 is a horizontal section on the line 4—4 of Fig. 1.

Fig. 5 is a sectional detail on the line 5—5 of Fig. 4 looking in the direction of the arrow.

Fig. 6 is a sectional detail on the line 6—6 of Fig. 5 looking to the left.

Corresponding and like parts are referred to in the following description and indicated in the several views of the drawings by like reference characters.

The appliance comprises a box which contains a plurality of receptacles and a case inclosing the box to protect the same from the rays of the sun and to subserve the purpose of a jacket generally to prevent injury to the box and the quick heating of the contents thereof which is injurious to food in warm weather.

The case comprises a bottom 1, ends 2, a back 3, a top 4 and a front 5. The top 4 is hinged in any manner to the upper portion of the back 3 so as to swing upward into open position, as indicated most clearly in Figs. 1 and 2. The front 5 is hinged at its lower edge to the forward edge of the bottom 1 in any substantial and preferred way to admit of said front swinging downward into horizontal position, as indicated most clearly in Fig. 2 in which position it may form a support for any one of the receptacles of the kit or other article to be placed thereon. Suitable bracing means 6 sustain the front 5 in horizontal position and, as indicated, the bracing means consist of folding elements which are pivoted to one another and to the ends and front of the case. In order to maintain a close joint between the front 5 and the ends 2, grooves or channels 7 are formed along the ends of the front 5 to receive the forward vertical edges of the ends 2 when the front 5 is in closed position. In this manner the front prevents inward or outward displacement of the forward edge portions of the ends 2 when the case is closed. The top 4 has a depending rim 8 which is adapted to embrace the upper edge portions of the inclosing walls of the case, thereby holding the front 5 in closed position when the case is shut. It is to be understood that the case when closed will be made secure by suitable locking means, not shown.

The box located within the case is of such relative proportions as to leave a space A between the contiguous walls of the case and box to prevent the heat from striking through on a warm day and quickly melting the ice and heating the food. While the box is detachably fitted within the case it is supported therein in a manner to prevent relative movement which would tend to produce a disagreeable noise when the vehicle

to which the appliance is attached is in motion. Any suitable filling means such as a strip B may be located in the space A to prevent relative movement of the box. The 5 box is indicated generally by the reference numeral C and like the case comprises inclosing walls such as a bottom, ends, front, back and top. The top of the box is designated by the reference letter C' and is 10 hinged to the back of the box so as to swing upward into open position. Fig. 6. A portion of the front of the box is cut away and is closed by means of a door C² which is hinged at its lower edge to the forward 15 edge of the bottom of the box. Opposite edge portions of the door C² are formed with grooves or channels c which receive outwardly extending portions at the ends of the opening which is closed by the door C². 20 This is shown most clearly in Fig. 4. When the door C² is closed it is held shut by the depending rim of the top C' which embraces the upper edges of the inclosing walls of the box. A vertical partition 10 divides the box 25 into two chambers, one of which receives an ice receptacle 11 and the other a plurality of receptacles for receiving different articles of food. Openings 12 are formed in the partition 10 for the circulation of air and the 30 portions of the partition cut out to form the openings 12 are bent laterally to form rests 13 to serve as supporting means for the food containing receptacles. The ice receptacle 11 may be of any capacity and is 35 fitted with a cover 14 which closes tightly to prevent the splashing out of water resulting from melting of the ice.

Rests 13 are provided on the opposite end wall of the chamber in which are disposed 40 the food receiving receptacles to act jointly with the rests 13 for supporting the receptacles. Two receptacles 16 and 17 are disposed one above the other in the upper portion of the food chamber and extend the entire length and width of said chamber and are adapted to receive food of any nature. Other receptacles 18 and 19 are disposed in the lower portion of the food chamber one beside the other and are also intended to 45 receive food of any nature. The receptacle 18 is closed by means of a cover 20 and is adapted to receive butter, preserves or the like. The several receptacles 16, 17, 18 and 19 are constructed in the form of trays or 50 boxes so as to contain articles of food of any nature and keep them separated. The top receptacle 16 is removable through the upper end of the box C whereas the remaining receptacles are removable through 55 the front of the food chamber which is closed by means of the door C². By having the receptacles removable from the box access is readily had thereto for placing food therein or removing food therefrom and 60 also to admit of the parts being thoroughly 65

cleansed and made accessible for any desired purpose.

It is to be understood that a lunch kit embodying the invention may be constructed of any suitable material and be of any capacity and form but in the preferable construction the device is constructed of sheet metal such as galvanized iron, zinc or tin. Any means may be provided for securing the device to the running board of an automobile or to any convenient part of the machine. It is also understood that the device may be carried upon the vehicle in any convenient way. The ice for preserving the food is placed in the receptacle 11 and the food according to its nature is distributed in the several receptacles and is kept cool by the circulation of the cool air resulting from the ice contained in the receptacle 11. Inasmuch as the ice receptacle 11 may be thoroughly cleansed and is provided with a close fitting cover the water resulting from melting of the ice may be used for drinking purposes. By reason of the construction of the device the ice will not be quickly melted when the appliance is exposed to warm air on a summer's day because the air space between the opposing sides of the box and case prevents the heat reaching the box containing the ice and food.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. In a lunch kit of the character set forth, a box, a partition dividing the box into chambers and having portions cut therefrom and bent laterally to form rests, and receptacles supported upon such rests, the openings formed by the rests providing for a circulation of air.

2. A lunch kit, comprising a case having a hinged top and a hinged front, bracing means for supporting the front in horizontal position, a box disposed within the case and spaced therefrom and having a hinged top and a hinged front portion, a partition dividing the box into ice and food chambers and having openings therein for the free circulation of air, an ice receptacle removably fitted in the ice chamber and a plurality of receptacles disposed in the food chamber and removable therefrom through the top and the open front thereof.

In testimony whereof I affix my signature.

SAMUEL B. SULLIVAN.
